UNITED STATES PATENT OFFICE.

ELKAN GOSLINER, OF SAN FRANCISCO, CALIFORNIA.

DESIGN FOR A FAVOR.

58,745.

Specification for Design. Patented Aug. 30, 1921.

Application filed April 13, 1921. Serial No. 461,100. Term of patent 14 years.

To all whom it may concern:

Be it known that I, ELKAN GOSLINER, a citizen of the United States, resident of the city and county of San Francisco, State of California, have invented a new, original, and ornamental Design for Favors, of which the following is a specification, reference being had to the accompanying drawing, forming part thereof, wherein—

Fig. 2 is a bottom plan view of the favor.

I claim:—

The ornamental design for a favor, as shown.

In witness whereof I have hereunto signed my name in the presence of witnesses at the city and county of San Francisco, State of California, this 28th day of February, 1921.

ELKAN GOSLINER.
